SHOULDER STRAP PADS
Harriet B. Dopyera, 1888½ Harbor Blvd.,
Costa Mesa, Calif.
Filed Dec. 21, 1959, Ser. No. 861,059
4 Claims. (Cl. 2—2)

This invention pertains to new and improved shoulder strap pads.

A number of different garments are constructed so as to include straps which extend over the shoulders of an individual. Because of the nature of such garments and various stresses and strains placed upon them during their use considerable pressure is not infrequently exerted upon the shoulders of an individual through such straps. Since these straps are normally of comparatively small dimension as far as width is concerned, and are of an extremely flexible character, the stresses and strains incurred during the use of such garments are concentrated in relatively small areas. As a consequence of these factors a good many individuals have difficulty in comfortably wearing various garments of the type indicated in the preceding discussion.

The problems indicated in the preceding discussion as being attendant to the use of garments supported by shoulder straps are not confined to the clothing field, however. Similar problems are found wherever straps are used to support a weight upon the shoulders of an individual. Thus, for example, hikers and the like carrying various types of back packs and related equipment frequently suffer from a certain amount of shoulder fatigue caused by straps cutting into their shoulders. Problems of this category are also encountered by individuals carrying heavy camera cases, and various other articles.

A broad object of the present invention is to provide new and improved shoulder strap pads for use in distributing forces exerted through straps upon the shoulders of an individual. Another object of the present invention is to provide shoulder strap pads which may be easily and conveniently manufactured at a comparatively nominal cost, and which, although inexpensive, are very effective for the purpose intended and are very easily utilized by an individual. These and various other objects and advantages of this invention will be more fully apparent from detailed considerations of the remainder of this specification including the appended claims and the accompanying drawing in which:

FIG. 1 is a top plan view of a presently preferred embodiment of a shoulder strap pad of this invention;

FIG. 2 is a cross-sectional view, taken at line 2—2 of FIG. 1;

FIG. 3 is a cross-sectional view taken at line 3—3 of FIG. 1;

FIG. 4 is a cross-sectional view, taken at line 4—4 of FIG. 1;

FIG. 5 is a top plan view of a modified shoulder strap pad of this invention; and

FIG. 6 is a cross-sectional view, taken at line 6—6 of FIG. 5.

Those skilled in the art to which this invention pertains will realize from a consideration of the accompanying drawing and of the remainder of this specification that a number of differently appearing shoulder strap pads may be designed and constructed on the basis of this disclosure through the use of routine design skill or ability. For this reason the accompanying drawing is not to be considered as limiting this invention in any respect.

As an aid to understanding this invention it may be stated in essentially summary form that it concerns shoulder strap pads, each of which includes an elongated, somewhat flexible backing strip having ends; a resilient pad

2

attached to one side of this backing strip, this pad covering substantially all of the backing strip; and at least two strap holders located generally at the other side of the backing strip, these strap holders being aligned with one another and being adapted to hold a shoulder strap so that such shoulder strap extends across this other side of the backing strip between the ends of it.

The actual nature of this invention will be more fully apparent from a detailed consideration of the accompanying drawing. In the initial figure of the drawing there is shown a shoulder strap pad 10 of the present invention having aligned ends 12 and sides 14 which are curved in a symmetrical manner so that the width of the pad 10 at its center between the ends 12 is greater than the width of the pad 10 adjacent to the ends of the pad 10. With the pad 10 there is used an elongated backing strip 16 and an elongated resilient pad 18. The backing strip 16 is smaller than the pad 18, although both have the same external shape. They both include side edges 14 and ends 12 as previously described, these side edges 14 and these ends 12 on the backing strip 16 and the pad 18 being located immediately adjacent to one another.

The backing strip 16 is preferably formed out of a somewhat flexible, yet somewhat stiff material, capable of distributing a load placed upon it by a strap 20 located so as to extend between the ends 12 over a comparatively wide or large area as compared to the area of this strap 20. A number of different materials can, of course, be used in forming the backing strip 16. It is presently preferred to form this backing strip 16 out of thermoplastic material having a limited amount of flexibility. Particularly favorable results have been achieved using such materials having a flexural strength of in excess of 4,000 p.s.i. such as medium or low density polyethylene, various vinyl polymers and copolymers, various nylon molding compositions, various synthetic rubber or the like. The entire backing strip 16 should preferably be of a "solid" nature and should not contain various pores or the like such as are commonly found in foamed materials. However, for purposes of ventilation it is preferred to space periodically throughout the backing strip small holes 22 which extend between sides 24 and 26 of this backing strip.

The side 26 of the backing strip is attached by an appropriate known adhesive (not shown), by fusion or by other means known to the plastics art to the pad 18. This pad 18 is preferably formed out of a flexible, resilient, foamed composition such as, for example, natural rubber, neoprene, butadiene-styrene copolymers, polyvinyl chloride or polyurethane materials. It is presently preferred that the pad 18 be of an "open cell" category in that the various cells or pores within it are largely connected to one another. This is preferred since with this type of structure a certain amount of ventilation is achieved through the pad 18, and the holes 22.

In order to satisfactorily hold the shoulder strap 20 upon the complete pad 10 it is preferred to locate upon the side 24 of the backing strip 16 at least two strap holders 28. In the complete shoulder pad 10 these holders 28 are formed as a part of the strip 16 and are located intermediate the ends 12 so as to be spaced from one another and so as to each be located adjacent to one of these ends. The holders 28 consist of small, elongated strap portions 30 which extend from the body of the backing strip 16 across elongated openings 32 of greater length than width, the lengths of these openings 32 corresponding to, and being slightly greater than the width of the strap 20. The openings 32 are located parallel to the ends 12. These strap portions 30 include ends 34 which are adapted to fit within raised pockets 36 formed generally beneath the side 24 of the backing strip 16. Preferably the strap portions 30 and the pockets 36 are

formed integrally with the entire backing strip 16 through the use of known injection molding processes or the like. When this is done the interiors of the pockets 36 are located generally adjacent to the side 26 of the backing strip 16 between it and the pad 18.

With the shoulder strap pad 10 it is presently preferred to utilize parallel longitudinal ridges 40 extending between the ends 12, which ridges are designed so as to loosely engage the edges of a strap such as the strap 20 so as to hold this strap in proper alignment between the ends 12 along the side 24 at all times. It is also preferred to utilize cross ridges 42 located closely adjacent to, but spaced from, the openings 32, these cross ridges 42 extending parallel to the openings 32. It will also be noted that the ridges 40 and 42 extend from the side 24 of the 15 backing strip 16, and are formed as an integral part of this backing strip.

With the complete shoulder strap pad 10 the holders 28 may be actuated so as to attach the strap 20 to this pad by first withdrawing the strap portions 30 from the 20 pockets 36. The strap 20 may then be laid in the position illustrated extending between the two ends 12. At this point the strap portions 30 may be reinserted within the pockets 36. Normally no additional means are necessary in order to hold the strap 20 with respect to the complete 25 pad 10. However, in order to provide for various abnormal forces which might tend to dislodge the strap 20 it is preferred to locate upon the ends 34 small bumps 44 which are adapted to fit within the correspondingly shaped depressions 46 within the interiors of the pockets 36 when the strap portions 30 are placed within these pockets. It is also preferred to form these strap portions 30 so that when they are released to an unstressed position they extend away from the side of the backing strip 16. When the strap portions 30 are formed of materials 35 as indicated so as to be integral with the backing strip 16 in this manner they tend to spring away from the pad 18 when used so as to firmly latch the ends 34 of these strap portions 30 within the pockets 36.

When the strap portions 30 are used as described in 40 the preceding they serve to deform the strap 20 in substantially a U-shaped configuration as indicated in FIG. 4 so that this strap bears directly against the cross ridges 42. As a result of the configuration forced upon the strap 20 as indicated in FIG. 4 a strap such as the strap 20 is firmly held by the complete pad 10 so that there is little tendency for relative motion to occur such a 45 strap and the complete shoulder strap pad 10.

In FIG. 5 of the drawing there is shown a modified shoulder strap pad 50 of the present invention which is essentially similar to the shoulder strap pad 10 previously described. For convenience of description those parts of the pad 50 which are identical to, or substantially identical to corresponding parts of the pad 10, are not 50 separately described herein, and are designated both in this description and the accompanying drawing by the primes of the numerals previously employed to designate such parts.

The pad 50 is of a generally rectangular configuration and uses straight side edges 14' instead of curved side edges as utilized in the pad 10. In the pad 50 a layer of protective fabric 52 is located around the resilient pad 18' and is folded under this pad so as to be held in place by being bonded to both it and the strip 16' adjacent to the surface 26' through the use of the same means used to secure the pad 18' and the strip 16' to one another. This fabric layer 52 tends to protect this pad 18' against various factors tending to damage it. In the pad 50 the various ridges and the like utilized in the pad 10 are not employed since they are not required in order to

form a satisfactory complete shoulder strap pad, although in many cases they are most desirably utilized.

It is generally preferred to form the pad 50 of heavier gage materials than are employed in the pad 10 so as to utilize this pad 50 with various heavy straps such as shoulder case straps, knapsack straps and the like. Because of shape, and size and anti-slipping features it is normally preferred to utilize the shoulder strap 10 with various garments of a personal nature so as to serve as protectors for the shoulders of an individual.

It will be realized from a consideration of the foregoing that a number of differently appearing shoulder strap pads falling within the scope of this invention may be designed through the use of routine engineering skill or ability. For this reason the present invention is to be considered as being limited only by the appended claims forming a part of this disclosure.

I claim:

1. A shoulder strap pad which comprises: an elongated backing strip formed of a thermoplastic material having a limited amount of flexibility, said strip having substantially a flat top and a flat bottom and having opposed ends, and being adapted to be used in conjunction with a shoulder strap extending across said top side between said ends, said backing strip including two openings extending between said top and said bottom, each of said openings being located adjacent to one of said ends, said openings extending across the path taken by a shoulder strap extending between said ends of said backing strip, said backing strip including integral strap means formed thereon at one extremity of each of said openings on one side path and integral pocket means for receiving and holding an end of one of said strap means located on the other side of said path at an extremity of each of said openings; a flexible, resilient foam pad secured to said backing strip so as to extend along and cover said bottom side of said backing strip, said flexible resilient foam pad being spaced from said pocket means so that a shoulder strap may be located so as to extend along said path and said strap means may be placed over a shoulder strap extending along said path so as to hold said shoulder strap within said openings and so that the extremities of each of said strap means can be located within said pocket means so as to retain said shoulder strap in place.

2. A shoulder strap pad as defined in claim 1 wherein said backing strip is formed out of a material having a flexural strength of at least 4000 p.s.i.

3. A shoulder strap pad as defined in claim 1 including ridge means for engaging the side edges of a shoulder strap extending across said top in order to hold said shoulder strap in place on said top of said backing strip, formed on said top of said backing strip so as to extend generally between said ends of said backing strip.

4. A shoulder strap pad as defined in claim 1 including ridge means for engaging a shoulder strap in order to prevent movement between said strap and said backing strip, said ridge means being formed on said top adjacent to said openings and said strap means.
